UNITED STATES PATENT OFFICE.

THOMAS A. DELANEY AND BENJAMIN T. McCANNA, OF CHICAGO, ILLINOIS,
ASSIGNORS TO THE HILLS-MCCANNA COMPANY, OF SAME PLACE.

LUBRICATOR.

SPECIFICATION forming part of Letters Patent No. 659,166, dated October 2, 1900.

Application filed March 12, 1900. Serial No. 8,294. (No model.)

To all whom it may concern:

Be it known that we, THOMAS A. DELANEY and BENJAMIN T. McCANNA, of Chicago, Illinois, have invented certain new and useful 5 Improvements in Lubricators, whereof the following is a specification.

Our invention relates to the class of lubricators in which the lubricant is drawn from a reservoir and forced to the point of application by one or more pumps.

The objects of our invention, as also the particular subject-matter which we consider novel, may be best explained in the subjoined description of an apparatus which embodies it in what we consider its best form and which we have illustrated in the accompanying drawings.

In the drawings, Figure 1 is a front elevation of a lubricator with six pumps. Fig. 2 is a rear elevation of the same. Fig. 3 is a side elevation of the same. Fig. 4 is a plan view of the same. Fig. 5 is a sectional elevation of one of the pumps, taken longitudinally through the body of the pump and through the discharge. Fig. 6 shows the ratchet and pawl for driving the pumps. Fig. 7 shows the means for operating the pawl from an irregularly-moving part of an engine, such as the valve-rod of a locomotive. Fig. 8 is a longitudinal section of an indicator for showing whether the lubricator is feeding.

In the several figures, 1 represents a reservoir for containing a lubricant. This reservoir is provided with a filling-hole at a suitable point and with a screen 2 therein.

3 are pumps mounted on the reservoir and corresponding in number with the number of points to which the lubricant is to be forced. The construction of these pumps is more particularly shown in Fig. 5 and will be described farther on. They are arranged near together in a series, so that they may all be operated by a single cross-head.

4 is the cross-head by which the pumps are operated. The cross-head is guided in its movement by the guide-studs 5 and is provided with ears 6 to engage the pump-plungers and is operated by the part to be next described.

7 is a shaft journaled in a standard 8, which is mounted on a reservoir 1. This shaft 7 is

provided at one end with a crank, whose pin 8^a plays in a slot 9 in the cross-head 4, thereby reciprocating the cross-head when the shaft is rotated. At its other end the shaft is provided with a ratchet-wheel 10, by which it is rotated.

11 is a gravity-dog for preventing a retrograde rotation of wheel 10.

12 is a sleeve loosely mounted on the shaft 6^a 7 and connected by screws 13 to a loose disk 14, which is provided with an arm 15, carrying a pawl 16.

17 is an arm on the sleeve, which is oscillated by a rod 18 or otherwise, thereby oscillating the sleeve, the disk, and the pawl, and so rotating the shaft 7 with a step-by-step motion, and thus reciprocating the cross-head 4 and operating the pumps. By means of the screws 13 the pawl-carrying arm 15 may be 7^a brought into any desired relation to the operating-arm 17, thus making it possible to have the pawl on the upper part of the wheel 10 whatever may be the position of the driving-arm. This enables us to use a gravity- 75 pawl and dispense with a spring for keeping the pawl in engagement. The arm 17 is oscillated through the rod 18 or some equivalent mechanism from any convenient moving part of the engine to be lubricated. In some cases 8^a 80 this moving part has a motion which is irregular—as, for example, the valve-rod of a locomotive, whose motion varies with the point of cut-off to which the valve is set at the moment. In such cases we attach to the valve- 85 rod or other moving part to which we wish to connect a cam-piece 19, (shown in Fig. 7,) in which 20 is the valve-rod to which the cam-piece 19 is attached, and 21 is a bell crank lever pivoted at 22 to some convenient fixed point 9^a 90 and provided with a friction-roller 24 on its arm 23. The end of the upright arm is connected to the rod 18. It will be observed that the cam-slot 25 in the piece 19 has an oblique section near its middle and that the two end sections are parallel with the travel of the device. The oblique section corresponds in length with the shortest travel of the rod 20, so that whatever the travel of the rod may be between that and full stroke the oscillation 95 of the lever 21 is the same, and consequently 100 the amount of lubricant pumped is the same.

In Fig. 5 we have shown the construction of our pumps. 26 is the body of the pump, which is provided with an ear 27, by which it is screwed to the top of the reservoir. 28 is the suction-valve, of spherical form, held in place by the pump-barrel 30, which screws into the body. 29 is the plunger moving in the barrel 30 and packed by some packing 31 between the barrel and the cap 32, screwed thereon. The upper ends of the pump-plungers are threaded and extend through the ears 6 of the cross-head 4. One or more nuts 33 and 34 on each side of the ears cause the cross-head to move the plungers as it travels up and down. The stroke of the plungers is thus regulated by setting the nuts 33 and 34 at a greater or less distance apart, thus allowing more or less lost motion to the cross-head. 35 is the discharge-valve of the pump, also of spherical form, pressed to its seat by a spring 36, whose tension is adjusted by a plug 37. This spring also serves where the apparatus is lubricating a steam-cylinder to close the valve and prevent the lubricant being sucked through by the vacuum resulting from shutting off steam from the cylinder. 38 is a union to connect the pipe 39, preferably of small diameter, which conducts the lubricant to the point of use. A similar small pipe 40 is screwed into the suction-orifice of the pump. If it be desired at any time to remove one of the pumps for any purpose, the screw 27 is taken out, thus disconnecting the pump from the reservoir. The plunger is then freed from the cross-head 4, the union 38 is disconnected, and the pump lifted right out of place. It is put back again by reverse operations.

To show whether the apparatus is actually feeding lubricant to the point of use or not, 40 we provide an indicator. (Shown more particularly in Figs. 4 and 8.) 41 is a cylinder interpolated in the feed-pipe at any convenient point, so that the lubricant passes through it, as indicated by the arrows—that is, from 45 42 to 43. 44 is a piston moving freely in the cylinder 41. The stem 47 of this piston extends through the cylinder and through a stuffing-box 45 and terminates in a button 46. When the apparatus is in operation, the piston 50 44, with the stem and button, will be pushed out by the lubricant till the piston is past the opening 43. If now it be desired to know whether the apparatus is feeding, the operator pushes the button in with his hand 55 and the stem and piston with it to the position shown. Then when he removes his hand the parts will be pushed out again by the lubricant moving through the device, thus giving an ocular demonstration that the apparatus is operating. When the piston is pushed clear out, it seats against the end of the cylinder, thus relieving the stuffing-box and shutting off the lubricant from it.

In some cases instead of the indicator of

Fig. 8 we use a pressure-gage 48, Fig. 3, on the discharge or feed pipe. This shows the pressure on the lubricant, and also by the vibration of the needle shows that it is feeding. If the needle does not vibrate, the operator knows at once that the feed has stopped, for we have discovered that when the lubricant is moving through the pipes the needle of the gage is in constant vibration.

49 is an ordinary glass gage to show the level of the liquid in the reservoir.

It is of course to be understood that the foregoing apparatus may be varied structurally in many respects without departing from our invention.

We claim—

1. In a lubricating apparatus, the combination of a reservoir, a pump for forcing the lubricant from the reservoir to the point of use, a cam-piece attached to a moving part of the engine lubricated, and provided with an oblique section and parallel sections and connections between said cam-piece and pump, whereby the pump receives a uniform stroke, independent of the variations in the stroke of the cam-piece, substantially as set forth.

2. In a lubricating apparatus, the combination of a reservoir 1, a shaft 7 rotatably mounted on the reservoir, one or more pumps 3 mounted on the reservoir, studs 5 on the reservoir, a cross-head 4 reciprocated on and guided by said studs and provided with one or more ears 6 to engage the pump-plungers, a connection between the cross-head and the shaft whereby the rotation of the former reciprocates the latter, and means for rotating the shaft, substantially as set forth.

3. In a lubricating apparatus, the combination of a pump, a discharge-pipe for the pump, a cylinder connected to said pipe, formed with an inlet and a lateral outlet for the lubricant, a plunger in said cylinder actuated by the lubricant passing through the pump discharge-pipe, and an external indicator connected to said plunger and adapted by its movement to show the motion of the lubricant in the pipe, substantially as set forth.

4. In a lubricating apparatus, a pump for forcing the lubricant comprising in combination a body containing the two valve-chambers, a pump-barrel adapted to be inserted in the body and limit the opening of the suction-valve, two valves of spherical form, a plunger adapted to the barrel, a spiral spring to close the discharge-valve, and a plug adapted to be screwed into the discharge-orifice against said spring, substantially as set forth.
